**BINARY COUNTER AND LOGIC GATES FOR
PROVIDING TRAFFIC FLOW CONDITION FOR TWO
SUCCESSIONAL BINARY COUNTS**

This application is a continuation of applicant's copending application Ser. No. 532,520 filed in the U. S. Pat. Office Feb. 21, 1966.

This invention relates to traffic control devices, subject to pedestrian actuation, to enable pedestrians to initiate a signal sequence which is intended to stop the vehicular traffic so that pedestrians can safely cross the street. Traffic signal indications may simultaneously provide the pedestrians with signal information intended to inform them when it is safe or unsafe for them to cross the through street. In the usual application, the combination of signals and control device is located approximately midway between street intersections and the controller will be referred to as a midintersection controller.

The invention, unlike those predominate in the art, employs no electromechanical devices except for the relays used to carry the signal light loads and the flasher to cause a flashing "DON'T WALK" signal. The entire controller involving all control functions may be readily and economically constructed of solid-state electronic components which are readily available and reasonably priced. The use of these components in the circuits to be described results in a traffic signal controller with no moving parts, with high reliability, requiring virtually no maintenance, impervious to the temperature extremes met in the usual applications and subject to economical production.

The usual application of this invention utilizes a standard RED, AMBER OR YELLOW, AND GREEN signal for the guidance of the motorist and a WALK-DON'T WALK signal for the guidance of the pedestrian. The signal lights will ordinarily display GREEN to the motorist and DON'T WALK to the pedestrian. Upon actuation of a push button by the pedestrian, the controller will react to change the signals in the following sequence:

Period	1	2	3	4	5	6	1
Vehicular direction	Green	Green	Amber	Red	Red	Red	Green.
Pedestrian direction	Don't walk	Don't walk	Don't walk	Don't walk	Walk	Flashing, don't walk	Don't walk.

Each of the periods except four Don't Walk, period 2, is separately, adjustably timed. Period 2 is untimed and is of indefinite length in the absence of pedestrian actuation. Provision for interrelated operation of the controllers is included. With this provision the instant of leaving period 2 is controllable. Thus controllers located at midintersection points may be coordinated with adjacent intersection controllers or with other midintersection controllers to avoid random stoppage of vehicular traffic.

In general, the operation of the controller results from the actuation of a push button. The push button operation sets up a "memory" circuit, which in conjunction with a coordinated circuit, energizes a short-timing circuit when REST condition is reached. This timing circuit, acting through an amplifier, causes a three-stage binary counting circuit to change from its static REST POSITION. Each subsequent position of the counter, through the use of "AND" gate circuitry, connects individual variable (timing) resistors to charge a timing capacitor. When the capacitor voltage reaches a definite predetermined value, the timing amplifier reacts to advance the counter through an additional position. At the instant of counter change, a resetting voltage is returned to discharge the timing capacitor and thus ready it for the next timing period. In each of the counter positions, the "AND" gates in addition to energizing the timing resistors, act through "OR" circuits to control lamp-load carrying relays and hence control the signal display. A voltage from the gate defining the WALK position restores the memory circuit to the nonactuated con-

dition. The controller counter will again remain at rest until a subsequent pedestrian pushbutton actuation is registered.

For further comprehension of the invention and of the objects and advantages thereof, reference will be had to the following description, the accompanying drawings and to the appended claims in which the novel features of the invention are more particularly set forth. The preferred embodiment of the invention will be described with reference to the following drawings in which like parts and interconnected terminal points are so designated and carried throughout the drawings.

FIG. 1 of the drawings is a block diagram of the midintersection controller, showing the basic functional modules of the controller as well as the interrelations between these functional modules. In this figure the numbers inside the box designate the figure where the module is shown in detail.

FIG. 2 shows detailed electronics of the pedestrian memory circuitry and the timing circuitry. The pedestrian memory circuitry records the actuation of a push button, or similar device by the pedestrian. The timing circuitry, associated with the timing potentiometers of (FIG. 5) control panel, controls the timing of the periods of signal display. All electronic components located in FIG. 2 are designated with the prefix T.

FIG. 3 includes the electronics of the counter which responds, in a sequential fashion, to impulses received from the timing circuitry of the FIG. 2. All electronic components located in FIG. 3 are designated with the prefix C.

FIG. 3A is a tabulated listing of the counter output conditions for each of the eight positions of the counter. The headings FF-1, FF-2, FF-3 refer to the three stages of the binary counter, in which the output is designated as either 0 or 1.

FIG. 4 shows the code gate circuitry used to enable the counter to provide outputs such that each counter position is enabled to energize an associated timing control potentiometer of FIG. 5. In addition, amplifying devices are driven so that output relays shown in FIG. 6 may be selectively, individually or concurrently energized. All electronic components located

in FIG. 4 are designated with the prefix G.

FIG. 5 shows the control panel which includes some control and indicating devices. The timing for each of the periods is controlled by means of variable resistors. The indicator lights show which of the periods is in effect. All electronic components located in FIG. 5 are designated with the prefix P.

FIG. 6 shows how the output relays are interconnected to provide the signal sequence desired. Components located in FIG. 6 are relays which are designated with the letter K.

FIG. 6A tabulates the signal indications resulting from the individual or combined energization of the output relays.

In the drawings and in the specifications, which here follow, like numerals indicate similar elements. Furthermore, the letter immediately preceding the numeral indicates the type of element. Thus, C-R 26 indicates: C in counter (FIG. 3), R a resistor and 26, the resistor numbered 26. The element identification is as follows: Q - transistor, D - diode, R - resistor, C - capacitor, K - relay, D S - indicator signal and SW - switch.

The circuitry and method employed to energize the signal lights will be explained to facilitate understanding of the total operation of the controller. When relays K 1, K 2 and K 3 (FIG. 6) are unenergized (the condition shown in FIG. 6), the signal lights displayed are RED and DON'T WALK. The circuit may be traced from the power source terminal through the center contact of K 1 B to the bottom contact of K 1 B and thence to the red signal. Similarly, the power source is fed to the bottom contact of K 3 B thence to the center contact of K

3 B, to the DON'T WALK signal.

In sequence, as listed in FIG. 6A, the relay and light conditions are as follows: When K 1 and K 2 are energized, the DON'T WALK signal is energized through K 3 B as before. The GREEN signal is energized from the power source to the center contact of K 1 B, to the top contact of K 1 B, to the center contact of K 2 B, to the top contact of K 2 B and thence to the GREEN signal terminal.

When K 1 alone is energized, the DON'T WALK signal is energized through K 3 B as previously described. The AMBER signal is energized from the power source to the center contact of K 1 B to the top contact of K 1 B, to the center contact of K 2 B, to the bottom contact of K 2 B, to the AMBER signal.

When K 1, K 2 and K 3 are energized, the circuit conditions lead to RED and DON'T WALK signal illumination.

When K 2 and K 3 are energized, the WALK signal is energized from the power source to the center contact K 1 A to the bottom contact K 1 A to the center contact K 2 A, to the top contact K 2 A, to the center contact K 3 A, to the WALK signal terminal. The RED signal is energized from the power source to the center contact of K 1 B to the bottom contact of K 1 B to the RED signal terminal.

When K 3 is energized, the energy from a pulsing or flashing source is fed from the top contact of K 3 B to the center contact of K 3 B, to the DON'T WALK terminal, to provide a flashing DON'T WALK signal. The RED signal is energized from the power source to the center contact of K 1 B to the bottom contact of K 1 B to the RED signal terminal. As will be further explained, the relays, K 1, K 2 and K 3, are energized by means of transistors G-Q 3, G-Q 2 and G-Q 1 (see FIG. 4). The controller is designed to provide selective operation of transistors G-Q 3, G-Q 2 and G-Q 1 as a result of the circuit logic, and the various input control signals. In order to better understand the operation of the controller, the several circuit subsections will be explained in detail and the interrelations between the circuits will be established.

The electronics requires several DC voltages to operate properly. These are derived from conventional rectifier, regulator and filter circuits, which require no description, since they are well known in the art. The voltages will be referred to as -6 v., +17 v., +22 v., and +27 v., which approximate the voltage levels used in one embodiment but which are not critical since by a different selection of components a different group of values might be used. Throughout this description, these voltages will be referred to by values indicated for convenience.

Transistors, C-Q 1 and C-Q 2 (see FIG. 3) form a monostable multivibrator. In addition, there is a three-stage binary counter consisting of transistors C-Q 8 and C-Q 7 as the first stage, C-Q 6 and C-Q 5 as the second stage, and C-Q 4 and C-Q 3 as the third stage. Each of these stages forms a bistable multivibrator (flip-flop) in which in each stage either of the transistors is able to conduct with the other nonconducting (cutoff).

Assume C-Q 8 is conducting; the path of conduction will be from the +22 v. through resistor C-R 17, through resistor C-R 32 through the collector - emitter path of C-Q 8, through resistor C-R 31 to the -6 v. source. Since C-Q 8 is in conduction, there will be a large voltage drop through C-R 32 and the voltage at the junction of C-R 27 and C-R 32 will be very low. The current drive to the base of C-Q 7 will consequently not be available and C-Q 7 will be nonconducting. As a result, there will be a drive from the +22 v. source through C-R 18, C-R 30 and C-R 28 to the base of C-Q 8, causing C-Q 8 to be held in the conducting condition. Transistor C-Q 8 will conduct and C-Q 7 will be nonconducting until a negative pulse is applied to the junction of capacitors C-C 13 and C-C 12. The negative going pulse, as will be shown, is obtained from the junction of C-R 7 and C-C 2. The negative pulse applied to the junction of C-C 12 and C-C 13 is applied to the base of C-Q 7 through C-D 7 and to the base of C-Q 8 thru C-D 8. Since C-Q 7 is already cutoff, no change in the condition of C-Q 7 can be

made. The negative pulse is applied to the base of C-Q 8 and to the collector of C-Q 7 through C-R 26. The negative pulse at the base of C-Q 8 causes C-Q 8 to conduct less readily and the voltage at the junction of C-R 27 and C-R 32 rises to provide a drive to the base of C-Q 7, causing C-Q 7 to conduct and further to reduce the drive through C-R 28 to C-Q 8. These combined actions act quickly to drive C-Q 7 into conduction and to cut off C-Q 8. Each successive negative going pulse will similarly change the state of conduction and of non-conduction of the C-Q 7, C-Q 8 combination. When C-Q 8 conducts, the voltage at the terminal 18 (FF-1) approaches -6 v., since C-R 32 is chosen so that its resistance is very much greater than the internal resistance of C-Q 8. At the same time, the voltage at terminal 23 (FF-1) approaches the +22 volt source because the current C-R 30 is very small due to the high resistance of C-Q 7 in its nonconducting condition. FF-1 is always opposite in value to FF-1. Thus when FF-1 approaches +22 volts, FF-1 approaches -6 volts and when FF-1 approaches -6 volts, FF-1 approaches +22 volts. FF-2 and FF-2; FF-3 and FF-3 are similar sets. A brief examination of FIG. 3 shows that C-Q 6 and C-Q 5 are associated components; and C-Q 4 and C-Q 3 are associated components are identical counterparts of C-Q 8 and C-Q 7 and its associated components.

When C-Q 8 changes from a nonconducting to a conducting condition the voltage at the junction of C-R 32 and C-Q 8 changes rapidly from approximately +22 volts to approximately -6 volts. This negative going voltage applied to the junction of C-C 9 and C-C 10, changes the conducting and nonconducting conditions of C-Q 6 and C-Q 5. When C-Q 6 changes from nonconduction to conduction, the negative going voltage produced at the collector of C-Q 6 changes the conducting and nonconducting conditions C-Q 4 and C-Q 3. If it is assumed that C-Q 8, C-Q 6 and C-Q 4 are all conducting, then the outputs at terminals 18, 19 and 20 will be very low and the outputs at terminals 23, 22 and 21 will be high. Low voltage is designated as 0 and high voltage as 1 (seen FIG. 3A), MIN. GREEN I is 0, 0, 0. The first negative pulse applied to the junction of C-C 13 and C-C 12 acts on C-Q 7 and C-Q 8 so that the output at 18 is high and the output at 23 is low. The first negative pulse thus causes the condition listed as MIN. GREEN II (1, 0, 0.). The next negative pulse to C-C 12, C-C 13 causes the negative pulse to appear at the collector of C-Q 8 which drives C-Q 5 into conduction. This condition is listed as REST I (0, 1, 0.). It will be seen that successive negative pulses at the C-C 12, C-C 13 junction produce the sequence of counter outputs listed in FIG. 3A.

It will be noted that the binary counter has eight positions. The traffic controller herein described requires only six positions. The conversion of an eight-counter into a six-counter is well known and is usually done by the use of feed back circuits requiring additional components. The method used in this invention involves an actual reduction of components. the MIN. GREEN is divided into two sections - MIN. GREEN I and MIN. GREEN II - each of which is timed for half the period required for MIN. GREEN, using the same timing element twice. The REST positions, untimed, is converted into two positions in a similar manner. It is apparent that this method can be utilized for any control device in which the control positions (number of) is less than the exact number of positions of the counter, with a consequent increase in dependency and economy of components.

When energy is first applied to the counter, it is important for safe traffic control that the counter and signals assume a definite predetermined position. The +22 voltage source is directed through C-R 18 to C-Q 7 through C-R 30, to C-Q 5 through C-R 23, and to C-Q 3 through C-R 12. Similarly, the +22 voltage source is directed through C-R 17 to C-Q 8 through C-R 32, to C-Q 6 through C-R 25 and to C-Q 4 through C-Q 14. Capacitor C-C 3 delays the application of the voltage through C-R 17. This action delays the application of the drive currents to the bases of C-Q 7, C-Q 5 and C-Q 3. Thus, at turn on, transistors C-Q 8, C-Q 6 and C-Q 4 will con-

duct more readily than C-Q 7, C-Q 5 and C-Q 3, placing the counter in the MIN. GREEN I condition. It will be seen that any turn on counter position can be predetermined by the connection of the collector resistors to either C-R 17 or C-R 18.

Transistor C-Q 2 is turned on from the +22 source through C-R 17 and C-R 2 to the base of C-Q 2. The -6 voltage applied to the base of C-Q 1 through C-R 4 prevents C-Q 1 from conducting. The voltage at the junction of C-C 2 and C-R 7 is consequently close to the +22 volt source. Transistor C-Q 1 can be driven into conduction by a positive pulse applied to its base. The positive pulse may be applied to terminal 10, and coupled to the base through C-C 7 and C-D 1 or it may be applied by grounding and then ungrounding the terminal 12. The resulting positive going pulse is coupled to the base of C-Q 1 by means of C-C 8 and C-D 2. Resistors C-R 5 and C-R 6 are used as discharge paths for C-C 7 and C-C 8 respectively. The change of C-Q 1 from the nonconducting to the conducting state causes the voltage at the collector of C-Q 1 fall rapidly. This action is coupled through C-C 2 to the base of C-Q 2, turning off C-Q 2 until C-C 2 becomes charged through C-R 2, whereupon if the positive going pulse no longer exists at the

outputs of G-Q 4 through G-Q 9 are applied to the transistors G-Q 1, G-Q 2, and G-Q 3. Transistor G-Q 9 drives G-Q 3 through G-D 26 and G-R 8; G-Q 9 drives G-Q 2 through G-D 27 and G-R 5. In a similar fashion, G-Q 8 drives G-Q 2 through G-D 25 and G-R 8; and drives G-Q 3 through G-D 24 and G-R 5. The output of G-Q 7 drives G-Q 3 through G-D 23 and G-R 8. The output of G-Q 5 drives G-Q 1 through G-D 3 and G-R 2; and drives G-Q 2 through G-D 4 and G-R 5. Resistors G-R 1, G-R 4 and G-R 7 connected to the -6 volt source provide positive turn off of G-Q 1, G-Q 2, and G-Q 3 when turnon drive is not present. Relay coil K 1 (see FIG. 6, relay panel) is connected to the +27 volt source, to terminal 28 and thence to the collector of G-Q 3. Relay K 1 will be energized whenever G-Q 3 is caused to conduct by the positive signal voltage through G-D 26, G-D 23, or G-D 25. Relay coil K 2 is similarly energized by means of G-Q 2, and relay coil K 3 is energized by means of G-Q 1. Thus the sequential and selective operation of the relays and the signal lights is controlled by the relay drive transistors, G-Q 3, G-Q 2 and G-Q 1 which are actuated by the gate amplifiers, which in turn are controlled by the counter-circuit. The following table lists the operation of the relay drive transistors, the relays and the signal lights.

Position	Relay drive transistors	Relays operated	Signals	Period
1. Min. green I	G-Q 3, G-Q 2	K 1, K 2	Green—don't walk	1
2. Min. green II	G-Q 3, G-Q 2	K 1, K 2	do	1
3. Rest I	G-Q 3, G-Q 2	K 1, K 2	do	2
4. Rest II	G-Q 3, G-Q 2	K 1, K 2	do	2
5. Clear	G-Q 3	K 1	Yellow—don't walk	3
6. All red			Red—don't walk	3
7. Walk	G-Q 1, G-Q 2	K 3, K 2	Red—walk	4
8. Walk clear	G-Q 1	K 3	Red—flashing, don't walk	5

base of C-Q 1, C-Q 2 will turn on once more. When C-Q 1 turns on, a negative step results at the collector of C-Q 1. This negative step is coupled to C-C 13 and C-C 12 to operate the counter. Simultaneously, a positive step results at the collector of C-Q 2. This positive step is fed to terminal 11 and is used to discharge the timer capacitor T-C 4 (FIG. 2).

The outputs of the counter (FIG. 3) are connected to terminals 18, 19, 20, 21, 22 and 23, of the code gates (see FIG. 4). Transistors G-Q 4, G-Q 5, G-Q 6, G-Q 7, G-Q 8 and G-Q 9 are emitter followers which are driven from the +22 volt source through G-R 3, G-R 6, G-R 9, G-R 10, G-R 11, G-R 12 respectively. The bases of the transistors are stabilized at +17 volts by the connection of the diodes G-D 33. It will be seen that the drive from G-Q 4 will not be present if either terminals 18, 19 and 20 is at a potential close to the -6 volt source; that is, G-Q 4 will conduct only if the cathodes of G-D 5, G-D 6 and G-D 7 are all at a potential sufficiently high so that there can be a current path from the +22 volt source through G-R 3 through the base emitter circuit of G-Q 4. A similar analysis will show that: G-Q 5 conducts when the cathodes of G-D 11, G-D 9 and G-D 10 are positive; this occurs when terminals 23, 19 and 20 are positive. The result is a voltage available at terminal 16.

The condition under which G-Q 6, G-Q 7, G-Q 8 and G-Q 9 conduct may be readily adduced. The following table summarizes the results:

Counter position	Positive input from counter at terminals	Conducting transistor	Output of gate at terminal
1.....	21 22	G-Q 9	24
2.....	21 22	G-Q 9	24
3.....	21 19	G-Q 8	14
4.....	21 19	G-Q 8	14
5.....	20 22 23	G-Q 7	25
6.....	20 22 18	G-Q 6	26
7.....	20 19 23	G-Q 5	16
8.....	20 19 18	G-Q 4	27

In addition to the voltage outputs at the terminals listed, the

outputs available at 24, 14, 25, 26, 16 and 27 are applied to the control panel (see FIG. 5). When the counter is in position 1 or 2, the voltage at terminal 24 illuminates indicator signal P-DS 3 which is connected to the common ground terminal. The voltage is also led to terminal 17 through P-R 8, variable resistor P-R 9 and diode P-D 3. Terminal 17 is similarly energized from terminal 25 through PR-5, variable resistor PR-6 and diode PD-2. Terminal 25 will be energized from terminals 26, 16 and 27 as the counter assumes successive positions.

The voltage at terminal 17 is utilized to charge the timing capacitor T-C 4 (see FIG. 2). Transistors T-Q 6 and T-Q 5 form a two-stage direct coupled amplifier. The emitters are elevated from ground by means of the voltage divider formed by T-R 19, temperature compensating diodes T-D 11 and T-D 12 and variable resistor T-R 20. Transistor T-Q 6 is biased so that it is essentially nonconducting. Transistor T-Q 5 is driven into conduction from the +17 volt source through T-R 18 and T-R 16. As a result the voltage at terminal 10 is slightly above that at the emitter of T-Q 5. The voltage at terminal 17 obtained through adjustable resistances P-R 9, P-R 6, P-R 3, P-R 18 or P-R 15 rises slowly when applied to the capacitor T-C 4. When the voltage rises to a value sufficiently high (as set by T-R 20) T-Q 6 is driven into conduction through diodes T-D 7 and T-D 10. When T-Q 6 is driven into conduction, the voltage at the junction of T-R 18 and T-R 16 goes down; this action deprives the base of transistor T-Q 5 of the drive formerly available through T-R 16; and T-Q 5 no longer conducts. Thus a positive going step is produced at terminal 10.

This positive going step is applied to the monostable multivibrator formed by C-Q 1 and C-Q 2 (FIG. 3). The result is, as previously described, that the counter moves one position. The positive going pulse at terminal 11 is directed to the base of T-Q 4 through diode T-D 9 and T-R 12. This pulse drives T-Q 4 into conduction, discharging T-C 4 through diode T-D 7 and also discharging T-C 2 through T-D 6.

Reference to FIG. 5 shows that voltage is available at terminal 17 except when the counter is in the REST position. The time for each of the positions, except REST, is determined by

the setting of the variable resistors such as P-R 9, P-R 6, et cetera, and T-C 4. The counter is taken out of the REST position by a combination of actions. These actions include a call from a pedestrian and a ground from the coordination control.

Transistors T-Q 1 and T-Q 2 (see FIG. 2) form a bistable multivibrator in which either of the transistors is conducting while the other one is nonconducting. When the counter reaches the WALK position, a positive signal is applied to terminal 16. This voltage is applied to the base of T-Q 1 through diode T-D 1 and resistor T-R 1, driving T-Q 1 into conduction. After the WALK period is concluded, an actuation of the pedestrian pushbutton places a ground at the junction of T-R 9 and T-R 2. The voltage divider composed of T-R 9, T-R 2 and T-R 15 is designed so that the voltage at the junction of T-R 2 and T-R 15 is normally positive. Grounding of the pushbutton causes the voltage at the junction of T-R 2 and T-R 15 to reach a negative value. This negative is transmitted by T-D 2 to the base of T-Q 1, causing T-Q 1 to stop conducting. Transistor T-Q 2 is driven into conduction from the +22 volt source through T-R 3 and T-R 6 to the base of T-Q 2. With T-Q 2 nonconducting, the voltage at the collector of T-Q 1 approaches the +22 volt value and is applied to the cathode of T-D 3.

Transistor T-Q 3 is driven into conduction by means of the +22 volts through T-R 7 and as a consequence the voltage at the collector of T-Q 3 is low. Grounding the coordination control terminal grounds the base of T-Q 3, removing the drive from T-Q 3, causing it to become nonconducting, thus raising the cathode of T-D 4 to a value approaching the source voltage. When the counter reaches the REST position, the cathode of T-D 5 is positive. A voltage is applied from the +22 volt source through T-R 10 and T-R 11 to charge T-C 2. The drive through T-R 11 operates T-Q 6 through T-D 6 and T-D 10 when T-C 2 is charged. The value of T-C 2 is chosen so that in combination with T-R 10 and T-R 11 it has a relatively small time constant. Thus as soon as the REST position is reached, the counter is moved to the next position provided there is a CALL registered and the coordination control is closed.

When the recall switch P-SW (FIG. 5) is closed, the REST position voltage, terminal 14, is fed to terminal 13 through P-R 11 to drive T-Q 2 into conduction. Thus a memory signal is registered during each cycle and the controller will recycle continually without the need for a pedestrian actuation.

The manual switch (see FIG. 2) is shown in the off position; when placed in the on position, a positive voltage is applied to the base of T-Q 4 through T-D 8 and T-R 12. This turns on T-Q 4 and prevents T-C 4 or T-C 2 from charging; there will be no timed control of the counter. The operation of the manual control places a ground on terminal 12. This ground is applied to C-R 16 (FIG. 3) dropping the voltage at the junction of C-R 16 and C-R 15. When the manual control is released, the voltage rises again and sends a positive pulse through C-C 8 and C-D 2 to C-Q 1. This action causes the counter to be pulsed into the next position.

While FIG. 6 shows the use of electromagnetic relays as output devices, these relays may readily be replaced by a combination of solid-state elements now commercially available.

It should be noted that the use of the two capacitors T-C 2 and T-C 4 (see FIG. 2) are both connected to enable controlled operation of the transistor amplifier T-Q 6. In practice, the value of T-C 2 is several magnitudes smaller than T-C 4, thus enabling an extremely wide divergence of periods without reducing the charging resistor T-R 11 to too small a value for practical purposes, or increasing the charging resistors P-R 9 to too large a value for practical purposes in operating the amplifier T-Q 6.

In order to avoid interfering unduly with vehicular traffic, a coordinating control signal may be introduced by momentarily grounding the base of T-Q 3, causing it to nonconduct and permitting the voltage at the cathode of T-D 4 to rise to +22 volts source value. The junction of T-D 5, T-D 3, T-D 4 and T-R 10 will be at ground potential unless the controller is at

REST, and the bistable multivibrator is set so that T-Q 1 is not conducting, and a coordinating signal is received so that T-Q 3 does not conduct. When all these conditions are met, the current can flow through T-R 11 to charge T-C 2, to operate T-D 5 10 and consequently move the counter out of the REST position.

It will be recognized that a permanent ground connected to the coordinating terminal enables the controller to respond to 10 change the signals immediately upon reaching the REST position.

The application of traffic controls of the type herein described requires that the cyclical characteristic is variable as a result of variations in pedestrian traffic demands and in addition it is necessary that the termination of the right-of-way for

15 the vehicles be controllable so that the moment of the termination can be coordinated, either simultaneously or at specific time spacing with other traffic controllers. The use of the transistors T-Q 1 and T-Q 2 connected as a bistable multivibrator and the use of the resistor network T-R 9, T-R 2 and T-R 15 connected between the +22 volt and the -6 volt

20 source permits a negative pulse to appear at T-Q 1 through diode T-D 2 when the junction of T-R 9 and T-R 2 is grounded by means of pedestrian action of the push button. It will be

25 seen that the accidental or malfunctional grounding of the connections to the pushbutton will also act to introduce a call to the bistable multivibrator. Thus a ground will not cause malfunction of the controller but will cause cyclical operation.

In traffic control systems, it is frequently necessary to provide for a specific number of output conditions which do not

30 correspond to the binary counter positions. In this invention, for example, the binary counter shown in FIG. 3, having three stages, has an output possibility of eight distinct conditions. The controller application, however, requires but six distinct

35 positions as listed in the period column of FIG. 3A. There are various schemes to connect binary counters into fewer position counters, all of which require additional electronic components for the required forcing feedback signals. The present invention discloses a way not only to avoid this forcing feed-

40 back method and its attendant components, but to reduce still further the number of components needed. Other advantages are also evident in the reduction of the variable resistor value while still obtaining a long timing period. It will be seen in FIG.

45 4 that the gate controlling G-Q 4 is composed of diodes G-D 5, G-D 6 and G-D 7, in turn controlled by the counter outputs FF 1, FF 2, and FF 3. Similarly, G-Q 5, G-Q 6 and G-Q 7 are controlled by gates each requiring an output from all three stages

50 of the binary counter. Transistor G-Q 9, however, is controlled from only two stages of the counter, namely, FF 2 and FF 3. Thus, G-Q 9 will be energized regardless of the position of the first stage of the counter, and consequently will be energized in two successive counter positions. The output of G-Q 9, fed to terminal 24, is in turn fed to the timing capacitor T-C 4 (see FIG. 2) through P-R 8, P-R 9 and P-D 3 (see FIG. 5).

55 The timing resistor P-R 9 is used in two successive counter positions. The total timing for these two positions represents the timing required for the MIN. GREEN. Not only have the feedback elements been eliminated to make the binary eight

60 into a six position, but in addition, the gating elements have been reduced as described. The principal described need not be limited to two successive counter positions but may also be extended to four positions, eight positions or "N" positions if a control device utilizing a binary counter must have its effective number of positions reduced. For example, in a four-stage counter the number of counter positions will be 16. If only 13 conditions are to be utilized, one of the positions may be repeated four times by removing the gating elements such as

65 diodes from control of the first and second stages of the counter. As a generality, if it is desired to utilize successive counter positions in one control period, the condition is readily created for 2^n positions where the gating elements for one of the output devices is removed from the first, second, third---- to the "N" stages of the counter output.

70 Although I have described and illustrated the preferred

form of the invention, it is understood that variations in the diagram and in the elements and in other minor ways without departing from the spirit and scope of the invention and therefore I do not limit myself to the precise construction herein disclosed and I reserve the right to all changes and modifications coming within the scope of the invention as defined in any of the appended claims.

I claim:

1. In a traffic controller for establishing a predetermined number of traffic flow conditions apparatus comprising:
 a binary counter having a group of cascaded stages and capable of assuming a plurality of counts greater than said predetermined number, the first of said stages being advanced only in response to an input signal on its input terminal to advance the count in said counter once for each input signal applied on said input terminal with the remaining ones of said stages being advanced only in response to a signal from the preceding stage,
 means for repetitively applying signals to said input terminal to thereby advance said count,
 logical circuit means coupled to said binary counter and

responsive only to the count in said counter for sequentially establishing said predetermined number of traffic flow conditions.

5 said logical circuit means including means for establishing at least one of said traffic flow conditions for at least two successive ones of said counts by responding only to the states of said remaining ones of said counter stages independently of the state of said first stage.

2. Apparatus in accordance with claim 1 and further comprising timing circuit means for controlling the duration in which said counter means resides with at least said at least two successive ones of said counts.

10 3. Apparatus in accordance with claim 1 wherein said predetermined number is six:

15 said binary counter is a three-stage counter with said plurality being eight,
 and said logical circuit means includes means responsive to binary 000 and 001 for establishing the first of said traffic flow conditions and means responsive to binary 010 and 011 for establishing the second of said traffic flow conditions.
